UNITED STATES PATENT OFFICE.

THOMAS B. HOWE, OF SCRANTON, PENNSYLVANIA, ASSIGNOR TO HOWE MANUFACTURING COMPANY, OF SCRANTON, PENNSYLVANIA, A CORPORATION OF PENNSYLVANIA.

DRIER.

SPECIFICATION forming part of Letters Patent No. 739,547, dated September 22, 1903.

Application filed April 14, 1903. Serial No. 152,564. (No model.)

To all whom it may concern:

Be it known that I, THOMAS B. HOWE, of Scranton, in the county of Lackawanna, State of Pennsylvania, have invented certain new and useful Improvements in Driers; and I do hereby declare the following to be a full, clear, and exact description of the same, reference being had to the accompanying drawings, forming a part of this specification, and to the letters of reference marked thereon.

This invention relates to improvements in driers, being especially designed for drying granular substances, as sand; and it has for its object to provide an apparatus through which the sand may be passed continuously and from which the moisture-laden air may be drawn off and one in which there will be no clogging or packing of the sand while passing through the apparatus.

To these ends the invention consists in certain novel details of construction and combinations and arrangements of parts, all as will be hereinafter described, and pointed out particularly in the appended claims.

In the drawings, Figure 1 is a side elevation of an apparatus embodying the present invention, a portion of the casing being broken away to show the interior construction. Fig. 2 is a horizontal section through two of the radiators and interposed air-chamber. Figs. 3 and 4 are detail views showing different forms of valve for regulating flow of material. Fig. 5 is a side elevation of a portion of one of the radiators.

Like letters of reference in the several figures indicate the same parts.

In the accompanying drawings, illustrating a practical embodiment of the invention, the letter A indicates a drying receptacle or chamber for receiving the material to be dried, preferably rectangular in shape and constructed of any suitable or desired material. This receptacle is suitably supported upon legs or supports A'. Within the receptacle or chamber A are located a series of heaters or radiators B, extending transversely of the chamber and arranged parallel from end to end of the drying-chamber. These radiators are each made up of sections b, suitably sup-

ported upon the floor of the chamber and bolted together by through-bolts b', passing through lugs b² at the top and bottom of the sections. The material to be dried passes between the parallel rows of radiators B, and to permit the radiators to be properly spaced apart to allow this each radiator-section preferably consists of two triangular-shaped portions b³. On opposite sides of the central line of the section and communicating with the interior of these portions b³ are hollow castings at the top and bottom of the sections, on the opposite sides thereof, cast integral with the sections, forming a passage for the steam or other heating medium through the radiators when the radiator-sections are bolted together, as will be readily understood. It is essential in devices of this character that the moisture-laden air or steam from the material should be drawn off and allowed to escape. For this purpose there is interposed between the parallel rows of radiators B air-chambers C, consisting, preferably, of a piece of sheet metal bent as shown in the drawings, the sides of said air-chambers abutting against the angular portions of the radiators, thus leaving a space between the radiators and air-chambers through which the material passes. The side walls of the air-chambers are provided with apertures c, preferably formed by slitting and bending the metal outward, as at c', forming an overhang over the aperture c, which will prevent the entrance of sand into the air-chamber. The overhang portion c' will loosen or break up the column of sand in its descent through the apparatus, thus permitting a ready escape for the moisture and a thorough drying of the sand. Steam as the drying medium is supplied from any suitable source through pipe D and branch pipes d, leading from said pipe to the bottom of the radiators, the steam being exhausted, if desired, after passing through the radiators through pipe E, communicating with the radiators at the top through branch pipes e.

For carrying off the vapor and moisture-laden air from the drying-chambers air-main F is provided, communicating with said

chamber by branch pipes *f*, a draft being preferably, created through the air-main *F* by means of a steam jet or nozzle *G*.

In order to regulate the flow of material through the drying-chamber, suitable valves, dampers, or other feed-regulators may be provided, bridging the space between the parallel rows of radiators.

The preferred form of valve consists of a cylinder or tube *H*, having cut-away portions *h* extending longitudinally of the tube on opposite sides thereof, said tube closed at each end and provided at one end with a hub or shaft *h'*, squared at the end for the reception of a suitable handle whereby the tube may be turned to cut off or permit the feed of the material, as will be readily understood.

The modification of the valve consists simply of a stationary plate *h³* and a movable plate *h⁴*, operated by means of handles *K*, said plates being provided with openings.

The sand or other material to be dried is supplied to the drying-chamber and after passing through said chamber, where it is thoroughly dried, is discharged at the bottom and, if desired, may be screened, a screen *L* being placed beneath the chamber for that purpose.

Having thus described my invention, what I claim as new, and desire to secure by Letters Patent, is—

1. In a drying apparatus, the combination with the radiators located therein, formed of sections having spacing projections and air-chambers located between the rows of radiators; substantially as described.

2. In a drying apparatus, the combination with the radiators located therein, formed of sections having spacing extensions on each side, air-chambers located between the rows of radiators and abutting against the extensions whereby spaces between the chambers and radiators will be left for the passage of the material through the chamber; substantially as described.

3. In a drying apparatus, the combination with the radiators, each formed of sections having triangular-shaped portions on opposite sides, passages cast integrally with the sections communicating with the interior of said triangular portions, air-chambers located between the radiators having openings for the escape of moisture, and abutting against the triangular portions, of the radiator-sections, whereby spaces will be left for the passage of the material through the chamber, and valves for regulating the flow of the material; substantially as described.

4. In a drying apparatus, the combination with the radiators located therein, formed of sections having integral spacing projections, of air-chambers formed of sheet metal located between the rows of radiators, having entrance-apertures, and overhanging portions above said apertures, said overhang portions constituting means for breaking up the column of material being dried; as and for the purpose set forth.

THOMAS B. HOWE.
